UNITED STATES PATENT OFFICE.

LEMUEL R. HOPTON, OF PLAINFIELD, NEW JERSEY, ASSIGNOR TO THE ENOS COMPANY, OF NEW YORK, N. Y., A CORPORATION OF NEW YORK.

DESIGN FOR A LIGHT-SHADE.

No. 39,661.

Specification for Design.

Patented Nov. 3, 1908.

Application filed August 8, 1908. Serial No. 447,644. Term of patent 7 years.

To all whom it may concern:

Be it known that I, LEMUEL R. HOPTON, a citizen of the United States, residing at Plainfield, Union county, New Jersey, have invented a new, original, and ornamental Design for Light-Shades Suitable for Electric-Light Reflectors, &c., of which the following is a specification, reference being had to the accompanying drawing, forming part of the same.

Figure 1 is a side view of a light shade showing my new design and Fig. 2 is a bottom view of the same.

I claim:

The ornamental design for a light shade as shown.

LEMUEL R. HOPTON.
